DESIGN FOR A HANDBAG

Frank X. Hiltenbrand, New York, N. Y.

Application August 21, 1944, Serial No. 114,947

Term of patent 3½ years

(Cl. D87—3)

To all whom it may concern:

Be it known that I, Frank X. Hiltenbrand, a citizen of the United States of America, residing in New York city, county of New York, and State of New York, have invented a new, original, and ornamental Design for a Handbag, of which the following is a specification, reference being had to the accompanying drawing, forming part thereof, wherein,

Figure 3 is a fragmentary front view thereof showing the handle member removed from the closure and the bag broken away for convenience of illustration, and

I claim:

The ornamental design for a handbag, substantially as shown and described.

FRANK X. HILTENBRAND.
